CLOCK CABINET

Warren F. Bacon, City of Industry, Gordon L. Entler,
Chino, and Alan W. McKae, Corona del Mar, Calif.,
assignors to Molyneux Clocks

Filed Dec. 2, 1974, Ser. No. 528,886

Term of patent 14 years

Int. Cl. D10—01

U.S. Cl. D10—16

FIG.
1.

FIG. 2.

FIG. 3.

FIG. 1 is a front and right side perspective view of a clock cabinet showing our new design;

FIG. 2 is a top plan view, the bottom being plain and unornamented;

FIG. 3 is a front elevational view, the rear being plain and unornamented; and

FIG. 4 is a right side elevational view, the left side being a mirror image thereof.

We claim:

The ornamental design for a clock cabinet, as shown and described.

FIG. 4.
